(57) **CLAIM**

The ornamental design for disposable flatware with hatched design, as shown.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a top plan view of disposable flatware with hatched design showing my new design as embodied in a spoon; FIG. 2 is a bottom plan view of the spoon of FIG. 1; FIG. 3 is a left side view of the spoon of FIG. 1; FIG. 4 is a right side view of the spoon of FIG. 1; FIG. 5 is an end view of the spoon of FIG. 1 showing the utensil end thereof;

FIG. 6 is an end view of the spoon of FIG. 1 showing the handle end thereof;

FIG. 7 is a top plan view of disposable flatware with hatched design showing my new design as embodied in a fork; FIG. 8 is a bottom plan view of the fork of FIG. 7;

FIG. 9 is a left side view of the fork of FIG. 7; FIG. 10 is a right side view of the fork of FIG. 7; FIG. 11 is an end view of the fork of FIG. 7 showing the utensil end thereof;

FIG. 12 is an end view of the fork of FIG. 7 showing the handle end thereof;

FIG. 13 is a top plan view of disposable flatware with hatched design showing my new design as embodied in a knife; FIG. 14 is a bottom plan view of the knife of FIG. 13; FIG. 15 is a left side view of the knife of FIG. 13; FIG. 16 is a right side view of the knife of FIG. 13; FIG. 17 is an end view of the knife of FIG. 13 showing the utensil end thereof; and,

FIG. 18 is an end view of the knife of FIG. 13 showing the handle end thereof.
